UNITED STATES PATENT OFFICE.

JOHN S. BAKER, OF BALTIMORE, MARYLAND, ASSIGNOR TO THE AMERICAN PATENT UNDERWEAR COMPANY, OF EXETER, NEW HAMPSHIRE.

CHEMISE.

SPECIFICATION forming part of Letters Patent No. 233,462, dated October 19, 1880.

Application filed March 31, 1880. (No model.)

To all whom it may concern:

Be it known that I, JOHN S. BAKER, of Baltimore, in the county of Baltimore and State of Maryland, have invented a new and useful Improvement in Chemises; and I do hereby declare that the following is a full, clear, and exact description of the same.

My invention relates to the manufacture of chemises and like garments; and it consists in the peculiar construction of the garment in respect to several details hereinafter specified, and in the mode of making said garments.

In the drawings hereunto attached and forming part of this specification, Figure 1 represents the completed garment, and Fig. 2 the cloth or pattern from which the garment is made.

Heretofore it has been customary in making such garments to form them of separate pieces cut approximately to fit the body, and when ruffling was desired about the neck and arms to add it by sewing said ruffling to the garment.

My invention aims to form the entire garment preferably out of one piece, and to form the ruffling out of the cloth which constitutes the body of the garment by the same gathering which gives the garment shape.

In carrying out my invention I cut the cloth to form the chemise in the shape shown in Fig. 2, in which *a* is the opening about the neck, *b* the parts which are to form the arms, and *c c* front and rear of the garment. The parts *c c* are then folded exactly upon each other, so that the edges coincide, and the side seams are sewed up, as shown at *dd* in Fig. 1. These may be sewed as plain seams, without any gathering. To form the neck, however, and to give the proper shape to the garment, that part of the cloth on the line *ee* about opening

a in Fig. 1 is gathered either by hand or on any machine fitted for the purpose, the amount of gathering being properly adjusted to give the desired shape to the garment.

The line of sewing, as indicated at *hh*, is a little removed from the edge of the cloth, so as to leave a ruffle attached about the upper part of the garment, thereby obviating the necessity of sewing on additional ruffling independently of the material of the garment itself.

After the gathering has been formed a strip or band, *k*, of any suitable material is sewed on over the line of the gathering, so as to conceal the threads and to strengthen the garment and add to its appearance. The arms are formed in the same manner as the neck, the parts being gathered and covered with bands, as shown at *ll*. Obviously the exposed edges, before being gathered, may be hemmed in the ordinary manner.

After the gathering has been formed a strip or band, *k*, of any suitable material is sewed on over the line of the gathering, so as to conceal the threads and to strengthen the garment and add to its appearance. The arms are formed in the same manner as the neck, the parts being gathered and covered with bands, as shown at *ll*. Obviously the exposed edges, before being gathered, may be hemmed in the ordinary manner.

Having thus described my invention, what I claim as new and desire to secure is—

The described garment cut with enlarged openings and fitted by gathering, the gathered edge being strengthened by a band, *l*, and constituting the ruffled edge, all as set forth.

In testimony whereof I have signed my name to this specification in the presence of two subscribing witnesses.

JOHN S. BAKER.
